PORTRABLE TRAY AND GLASS HOLDER COMBINATION

Margaret H. Labik, 540 Bird St.,
Wadsworth, Ohio 44281

Filed Feb. 27, 1974, Ser. No. 446,136

Term of patent 14 years

Int. Cl. D6—99

U.S. Cl. D6—20

FIG. 2

FIG. 3

FIG. 1

FIG. 4

FIG. 5

FIG. 1 is a side elevational view of a portable tray and glass holder combination embodying my new design.

FIG. 2 is a top plan view thereof.

FIG. 3 is a bottom plan view thereof, partially in section and taken substantially along line 3—3 of FIG. 1.

FIG. 4 is a modified form of the portable tray and glass holder combination shown in FIG. 1.

FIG. 5 is a bottom plan view partially in section and taken substantially along line 5—5 of FIG. 4.

The top surface of the tray shown in the FIG. 4 embodiment is plain and unornamented.

I claim:

The ornamental design for a portable tray and glass holder combination, as shown and described.
